UNITED STATES PATENT OFFICE.

CHARLES M. STEINMETZ, OF WASHINGTON, DISTRICT OF COLUMBIA.

SHIRT HAVING REVERSIBLE SOFT CUFFS.

Application filed August 14, 1920. Serial No. 403,453.

To all whom it may concern:

Be it known that I, CHARLES M. STEINMETZ, a citizen of the United States, residing at Washington, in the District of Columbia, have invented certain new and useful Improvements in Shirts Having Reversible Soft Cuffs, of which the following is a specification, reference being had to the accompanying drawings.

10 This invention relates to shirts and shirtwaists having attached soft cuffs or "French" cuffs which are reversible, and particularly to the detailed construction of the folding soft cuff and to the formation 15 of the placket or vent of the shirt sleeve to which the cuff is attached.

One of the objects of my invention is to provide a folding soft cuff for shirts and shirtwaists so designed and made as to reduce undue wear and tear at the edges of 20 the fold lengthwise of the cuff.

The attached foldable soft cuffs ordinarily found on shirts tend to wear, break and fray at the fold of the cuff and the outer surface 25 or layer of material is very apt to wear away and the inner lining show through the cuff, if there is any inner lining, or the inner surface of the goods will show through the cuff. This is eliminated by the construction 30 which I have designed.

Another objection in foldable soft cuffs is that when the outer end portion of the cuff is folded inward to present a new and clean surface upon the exterior of the cuff 35 and the hand thrust through the shirt sleeve, the inwardly turned portion of the cuff is very liable to be forced outward by the hand and the cuff is very hard, therefore, to adjust, and even after the hand is thrust 40 through the shirt sleeve, the inwardly turned portion of the cuff tends to work down the wrist and the cuff loses its fresh folded appearance and becomes rumpled.

Another object of my invention is to avoid 45 this by providing means, which, when the cuff is turned inward, engages the margin of the cuff with the sleeve all around the cuff so that the inwardly turned portion of the cuff will be held firmly in place and prevented from rumpling.

And another object of my invention connected with the last is to provide means for concealing this fastening means when the outer end of the cuff is turned outward so 50 that there will be no indication upon the ex-

terior of the cuff of any such attaching means.

A further object of my invention is to so form the placket or vent as to secure a perfect fit and finish to the shirt sleeve 60 where soft cuffs or French cuffs are used. The reinforcing bands of the vents of shirt sleeves today have a strip of goods continuous on the inner surface and the upper ends of these bands are so made that there 65 is a twist and wrinkle in the band and sleeve, making it fit imperfectly where soft cuffs are attached to the sleeve.

And a further object of this invention is to provide a strong, durable, and non-ripping reinforcement along the edges of a placket or vent so constructed as to permit the sleeve and cuff to lie flat without any tendency to twist and wrinkle and which will cause the foldable cuff and sleeve to fit 75 more perfectly and give a better finish to the shirt sleeve than is the case at the present time.

Other objects will appear in the course of the following description. 80

My invention is illustrated in the accompanying drawings, wherein:—

Figure 1 is a perspective view of a shirt sleeve having my improved cuff and placket band attached thereto; 85

Figure 2 is a sectional view through the shirt sleeve and the cuff, looking at the inside of the shirt sleeve and showing the cuff folded or reversed inside of the shirt sleeve;

Figure 3 is a face view of a fragment of 90 the cuff and shirt sleeve, showing the cuff open or entirely unfolded;

Figure 4 is a like view to Figure 2 looking at the inside of the sleeve, but showing the cuff turned to face outward, that is reversed with relation to Figure 2; 95

Figure 5 is a fragmentary perspective sectional view of a portion of a shirt sleeve looking at the inside face, the cuff being entirely unfolded; 100

Figure 6 is a perspective view of a portion of a shirt sleeve and the cuff showing the cuff upwardly turned upon the outer face of the shirt sleeve or reversely to the manner in which the cuff is turned in Figure 2; 105

Figure 7 is a fragmentary elevation of a portion of a shirt sleeve and cuff with my improved reinforcing placket band attached thereto, the band being partly broken away; 110

Figure 8 is an enlarged section on the line 8—8 of Figure 7;

Figure 9 is a longitudinal section on the line 9—9 of Figure 7;

5 Figure 10 is a plan view of the reinforcing band for the placket before it is folded;

Figure 11 is a perspective view showing the manner in which this reinforcing band is folded to form the placket reinforce.

10 Referring to these drawings, 10 designates the shirt sleeve of a shirt or shirtwaist. The folding soft cuff attached thereto is composed of two sections 11 and 12, each of these sections being preferably composed of two

15 plies of material joined at the inturned hems 13, the wrist band of the shirt sleeve 10 being attached to the plies of the section 11 by stitching. The section 11 has approximately the same size as the section 12, and disposed

20 between the margins of the sections 11 and 12 is a strip 15 of textile fabric preferably of the same character as that of which the cuff is made, which strip is attached to the sections 11 and 12 by stitching 14. This

25 strip 15 forms in effect a hinge between the sections 12 and 11, permitting the section 12 to be folded over upon the section 11, either upon the outside of the section 11, as shown in Figure 4, or the inside thereof, as in Fig-

30 ures 1 and 2. This strip comes at the normal fold of the cuff, that is, on the line that a cuff of this character would be ordinarily folded, and, therefore, permits the ready folding of the sections of the cuff upon each

35 other without any breaking or wearing of this portion of the cuff. This strip 15 may be of a single ply of fabric or a double ply, as desired. This construction lengthens the wear and life of the cuff because the fold and

40 the wear and tear upon the cuff come upon the strip connecting the two sections of the

cuff. Of course, the two sections of the cuff are provided with the usual four button holes

45 whereby the usual link cuff buttons may be passed through the two sections of the cuff to hold the cuff in its folded position. The

detailed manner of engaging the sections 11 and 12 with the strip 15 is shown in Figure 2 but not in the other figures.

50 Attached between the two plies of material forming the section 12 and having a length equal to that of the cuff is a strip 18 which is also preferably formed of two plies of mate-

rial stitched around its margin as shown in

55 detail in Figure 3, and this strip 18 on its inner face carries a plurality of snap fastener members, illustrated as elastic stud members and designated 19 (see Figure 3). These are stitched, eyeleted, riveted, or otherwise at-

60 tached to the inner ply of the two plies of material forming the strip 18 and coat with a series of snap fastener members, shown as socket members 20, stitched or otherwise attached to one of the plies of material forming the section 12. This strip 18 is adapted

to be folded over, as illustrated in Figure 6, upon the inner face of the margin of the section 12, and the stud members 19 engaged with the socket members 20. The inside of the shirt sleeve adjacent its point of engagement with the section 11 is provided with a series of socket members 21 of exactly the same character as the socket members 20 and disposed in approximately the same position. 70

Now when the section 12 is folded over 75 upon the outside of the section 11, as shown in Figure 6, the strip 18 is turned inward and the studs 19 engaged with the sockets 20, and in this case the cuff looks much the same as the ordinary folded cuff. When 80 the section 12, however, is to be folded inward upon the section 11, as shown in Figure 2, the stud members 19 are disengaged from the sockets 20 and engaged with the sockets 21 and, therefore, the edge of the section 12 85 of the cuff which is within the sleeve is firmly held to the sleeve so that when the hand and arm are passed through the shirt sleeve, the edge will not be caught by the hand and forced outward, but the cuff will 90 be held folded upon the line of the strip 15 in the usual manner, thus presenting a neat appearance which will remain, inasmuch as the cuff cannot become rumpled or forced down on the arm. 95

It is to be particularly noted that the section 11 is so attached to the sleeve 10 that there is a layer or ply of material upon the outer face of the shirt sleeve and that there is a slight margin 22 which is left free and 100 which simulates the edge of a cuff so that, when the section 12 is folded inside of the section 11, the fact that the section 12 has been folded inside is not observable, as this edge 22 gives the effect of the free edge of 105 the section 12.

While I have heretofore referred to this cuff as being an attached cuff, it will be understood that the principle of the invention might be applied to unattached cuffs, that is 110 cuffs not sewed to the shirt sleeve. It is also to be understood that I may use any fastening devices for the purpose of connecting the strip 18 to the inner face of the shirt sleeve or to the inner face of the section 12, though 115 preferably I use the snap fasteners, as illustrated.

It will be seen that my cuff functions in exactly the same manner as the ordinary foldable cuff, but that it has many advantages thereover, that it will wear longer than the ordinary cuff, stand more hard usage in the laundry, and is generally superior thereto. 120

The shirt sleeve 10 in the drawings is 125 illustrated as formed with the usual vent or slit extending inward from the cuff end of the shirt sleeve any desired distance. In order to reinforce this slit to prevent it tearing and at the same time secure a per- 130

fect fitting of the shirt sleeve with a reversible soft cuff, I reinforce the slit by means of a band 23 illustrated in Figure 10, this band being made of suitable textile material for the purpose. The middle portion of the blank from which the band is made is formed to provide the middle flaps 24 on opposite edges of the band and between this middle portion of the band and the ends of the band there is a portion 25 formed on each edge with a flap 26, the flaps 24 and 26 being separated from each other by V-shaped notches 27. This band 23 is creased or folded longitudinally on the line $x-x$. The middle portion Z of the band is creased longitudinally by the crease x and is also creased diagonally by the diagonally extending creases y , intersecting the notches 27.

In applying this band to the shirt, the two end portions of the band are folded in parallel relation, the creases y permitting this folding of the band, and the band then has the form shown in Figure 11. The flaps 24 are folded inward on the inner surfaces of the triangular middle portions 29 formed by folding as above described, while the flaps 26 are folded inwardly upon the inner faces of the longitudinally folded portions 25. Thus the folded band provides two plies of material on each side of the medial slot of the vent, between which plies of material the marginal edges of the shirt on each side of the slit C are inserted. The reinforcement thus formed is then stitched to the shirt by means of stitching 28, these lines of stitching passing through the folds or flaps 26 and the longitudinally folded portions 25 of the band and passing around the margins of the triangular portions 29 formed by folding the middle portion of the band as described, and across the face of the triangular portions, as clearly shown in Figure 7.

Two registering button holes 30 are formed in one portion of the band and a button 31 is attached to the other portion of the band, or a button hole may be disposed in place of this button 31 to permit a link to be used to cause the closing of the vent, or these button holes 30 and the buttons 31 may be left off entirely and snap fasteners used instead.

It will be noted that the material of the sleeve on both sides of the slit C is reinforced by two plies of material having turned-in hems or margins, and that the end of the slit is reinforced by practically four plies of material, two plies being on each side of the material of the shirt, thus preventing any danger of the vent tearing. Actual use of this reinforcing band has demonstrated that it provides for a very perfect fit for the shirt sleeve without any tendency to twist or wrinkle or open up, and adds a very attractive finish to the shirt sleeve, inasmuch as both margins of the vent or slit are finished in the same manner.

I claim:

1. In a body garment, a sleeve, a soft cuff attached thereto and foldable longitudinally along its medial line, the outer margin of the cuff having attached thereto a longitudinally extending strip foldable over upon the outer face of the cuff, said strip and the outer face of the cuff upon their confronting faces being provided with means for holding the strip folded upon the cuff, the shirt sleeve being provided upon its inside face with means for engaging said strip with the shirt sleeve. 70

2. In an article of apparel, a wrist surrounding body portion having an outer and an inner surface and having a portion adapted to be folded upon the outside of said body portion and upon the inside thereof, and means on the inside of the body portion engageable with said foldable portion to hold the margin of the foldable portion engaged with the inner face of the body portion. 80

3. In a garment, a wrist surrounding body portion having an outer and inner surface, a portion attached to said body portion and foldable over upon the outer surface thereof and upon the inner surface thereof, a strip attached to the free margin of the foldable portion and foldable inward thereover, the margins of the foldable portion of the strip upon their confronting faces being provided with coacting fastening devices, the inner surface of the body portion being provided with fastening devices with which said fastening devices on the strip coact when the foldable portion is turned inward on the body portion to thereby hold the margin of the foldable portion in close engagement with the inner face of the body portion when the foldable portion is turned inward. 90

4. In a garment, a shirt sleeve, a longitudinally foldable cuff attached thereto, a strip attached to the free margin of the cuff and foldable over upon the outside face of the cuff, the inner face of said strip and the outer face of the cuff being provided with coacting fastening devices, the inner face of the shirt sleeve adjacent its point of engagement with the cuff being provided with fastening devices coacting with the fastening devices on the strip when the cuff is folded inward to thereby hold the free margin of the cuff in engagement with the shirt sleeve. 110

5. In a garment, a shirt sleeve, a longitudinally foldable cuff attached thereto, a strip attached to the free margin of the cuff and foldable over upon the outside face of the cuff, the inner face of said strip and the outer face of the cuff being provided with coacting snap fastener members comprising resilient studs and coacting sockets, the inner face of the shirt sleeve adjacent 125

its point of engagement with the cuff being provided with snap fastener members adapted to coact with the snap fastener members on the strip when the cuff is folded inward 5 to thereby hold the free margin of the cuff in engagement with the shirt sleeve.

6. In an article of apparel having a vent slit, a reinforcing band therefor comprising a strip of material longitudinally and transversely folded to provide two plies of material forming each margin of the slit, the transverse fold of the material providing four plies of material at the ends of the slit, two of which plies extend across and intersect the closed end of the slit.

7. An article of apparel having a vent slit, a reinforcing band therefor comprising a single strip of material folded transversely at its middle to provide two parallel portions, each of these longitudinally extending, parallel portions being medially folded along its length to thus provide two superposed plies, each two plies embracing and being sewed to the material at the opposite margins of the vent.

8. In an article of apparel having a vent slit, a reinforcing band therefor comprising a strip of material having at its middle two diagonal creases, the strip of material being longitudinally creased on a medial line intersecting the intersection of said diagonal creases, said strip being folded on the said medial crease and upon its diagonal creases

to provide two parallel portions each formed of two plies of material and opposed triangular end portions, the material at the opposite margins of the slit being embraced between each two plies and sewed thereto and the triangular portions being sewed to the material at the end of the slit.

35 40

9. In an article of apparel having a vent slit, a reinforcing band therefor comprising a strip of material having at its middle two diagonal creases, the strip of material being longitudinally creased on a medial line 45 intersecting the intersection of said diagonal creases, said strip being folded on the said medial crease and upon its diagonal creases to provide two parallel portions each formed of two plies of material and opposed triangular end portions, the material at the opposite margins of the slit being embraced between each two plies and sewed thereto and the triangular portions being sewed to the material at the end of the slit, each of 50 55 said longitudinally extending plies being formed with an inwardly turned hem and each of the triangular plies being formed with an inwardly turned hem, the stitching connecting the reinforcement to the article 60 of apparel passing through said inwardly turned hems.

In testimony whereof I hereunto affix my signature.

CHARLES M. STEINMETZ.
